UNITED STATES PATENT OFFICE.

GEORGE S. TIFFANY, OF SUMMIT, NEW JERSEY, ASSIGNOR TO GRAY NATIONAL
TELAUTOGRAPH COMPANY, OF NEW YORK, N. Y., A CORPORATION OF VIR-
GINIA.

TELAUTOGRAPHIC APPARATUS.

1,085,069.

Specification of Letters Patent. Patented Jan. 20, 1914.

Application filed April 5, 1912. Serial No. 688,617.

To all whom it may concern:

Be it known that I, GEORGE S. TIFFANY, a citizen of the United States, residing at Summit, county of Union, and State of New Jersey, have invented certain new and useful Improvements in Telautographic Apparatus, fully described and represented in the following specification and the accompanying drawings, forming a part of the same.

10 This invention relates to improvements in telautographic systems of the variable current-strength type. In these systems as heretofore used, the pen-moving parts at the receiver have included magnetic coils connected with the right and left tracer lines from the transmitter, and moving in a suitably excited magnetic field (provided by magnets of the salient pole type) to an extent and in directions varying in accordance with the variations in the strength of the currents from time to time traversing the tracer lines, these variations in current strength being controlled and effected by the transmitting tracer as it is moved laterally over its writing platen.

I have discovered that if magnets of the consequent pole type be substituted for those of the salient pole type just referred to, a great saving of power, and, therefore, of current, may be effected, and it is the object of the present invention to provide a telautographic system equipped with such consequent pole magnets.

In the accompanying drawings Figure 1 is a diagrammatic view of a telautographic system embodying the present invention. Fig. 2 is a front elevation, partly in section, of the receiver pen-moving parts; and Fig. 3 is a side elevation of the same.

40 Referring to said drawings, A represents the transmitting instrument or transmitter, and B the receiving instrument or receiver. The former is provided with a current-supplying-circuit whose source of supply is a current generator 1, this circuit being traced as follows: From the positive pole of generator 1, by wire 2 to a rheostat 3, and by wire 4 to a rheostat 5, and wire 6 from rheostat 3, and wire 7 from rheostat 5, to 45 the negative pole of generator 1, which is grounded by wire 8 at 9. Currents from this circuit are shunted from right and left rheostats 3, 5, into right and left tracer lines to the receiver, which are traced as follows:

50 For the right line, a roller contact 10 en-

gaging right rheostat 3, a lever 11, wire 12, movable coil 13 of right hand consequent pole magnet 14, and thence by wires 15, 16, 17, to ground at 18; and for the left tracer line, a roller contact 20, engaging left rheostat 5, a lever 21, wire 22, movable coil 23 of left consequent pole magnet 24, and thence by wires 47, 26, 16, 17, to ground at 18. Levers 11, 21, are pivotally mounted and have rigidly connected with them levers 30, 31, which are pivotally connected with pen arms 32, 33, in the converging, pivotally connected ends of which is mounted the transmitting tracer 34 all in the usual, well-known manner. It will be obvious that, as the transmitting tracer 34 is moved laterally or over its writing surface or platen, roller contacts 10, 20 will be moved along the rheostats 3, 5, in directions and to extents depending on the direction 75 and extent of such movements of the transmitting tracer, and, as a result, currents, which vary in strength in accordance with such movements of the tracer, will be shunted into the right and left tracer lines, 80 just described, leading from the transmitter to the receiver and ground. These currents, as they vary in strength, in turn effect movements of the pen moving coils 13, 23, varying in extent and direction as the current increases or decreases in strength. These coils in turn move the receiving pen 35 laterally or over its writing platen 36 in unison with the movements of the transmitting tracer over its writing platen, 90 through connections which will presently be described. Each of the coils 13, 23, includes a cylindrical shell 37 on which the coil is wound and which is slidably mounted on the core 38 of the magnet, and inside the 95 magnet shell 39.

The stationary windings 40, 41 at opposite ends of the magnet are excited from a local source of electric energy, namely, a generator 42, by a circuit consisting of wire 100 43 from the positive pole of said generator, wire 44 connecting windings 40, 41 of magnet 13, wire 45, wire 46 connecting windings 41, 40 of magnet 23, and wires 25, 26, 16 to the negative pole of generator 42. 105 Each of the magnet shells 39 is provided with diametrically opposite longitudinal openings 48, and journaled in a bracket 49 at the upper or outer ends of these openings is a shaft 50. To this shaft are rigidly fixed 110

- a pair of segments 51, 52, which are connected by chains 53 with pins 54 fixed to shell 39 and projecting through the openings 48, so that as the coil 13 or 23 is drawn 5 downwardly or inwardly along the magnet core, shaft 50 will be rocked in a clockwise direction. A spring 55 secured at one end to a collar 56 fixed to shaft 50, and at the other end to a clip 57 fixed to a bolt 58, secured 10 in bracket 49, opposes such movement of the shaft 50 and moves it in the opposite direction as the currents traversing the coil 13 or 23 decrease in strength. The two shafts 50 are provided with levers 60, 61, rigidly 15 fixed to them, and pivotally connected with pen arms 62, 63, in the converging pivoted end of which the receiving pen 35 is mounted. It will be obvious that as the coils 13, 23 are moved different distances in their 20 magnet fields, as the currents traversing the right and left tracer lines vary in strength, receiving pen 35 will be moved across its writing platen 36 and reproduce the movements of the transmitting tracer.
- 25 The advantages of the consequent pole magnet system above described have been hereinbefore generally stated. In order that these advantages may be appreciated, I may add that with such magnets a length 30 of line or circuit may be operated which is between two and three times as long as the line or circuit which may be operated where salient-pole magnets, with the same size coil and the same size core are employed. This, 35 with the resulting saving in power and current consumed, is due to the fact that the poles of the magnet are magnetized at both ends, the total flux in the air gap surrounding the magnet case and in which the coil 40 moves is about doubled, and the force exerted by the moving coil also about doubled, assuming the current strength to be the same as in the case of the salient pole magnets.
- No means are shown or described herein 45 for effecting the movements of the receiving pen to and from its writing platen, nor for inking the receiving pen, or for shifting the paper at the receiver. Any suitable means for these purposes may be adopted.
- 50 What I claim is:—
1. In a telautographic register, of the variable current-strength type, the combination with tracer lines connecting the transmitter and receiver, a source of electric energy therefor, a transmitting tracer and connec- 55 tions controlling the strength of the currents traversing the tracer lines as the transmitting tracer is moved over its writing surface, a receiving pen, and pen-moving parts therefor including consequent pole magnets provided with movable coils connected with the tracer lines and with the receiving pen.
  2. In a telautographic system of the variable current-strength type, the combination with tracer lines connecting the transmitter and receiver, a current supplying circuit, a transmitting tracer and connections for shunting therefrom into the tracer lines currents varying in strength as the transmitting tracer is moved over its writing surface, a receiving pen, and pen-moving parts therefor including consequent pole magnets provided with movable coils connected with the tracer lines and with the receiving pen. 60
  3. In a telautographic register of the variable current-strength type, the combination with tracer lines connecting the transmitter and receiver, a source of electric energy therefor, a transmitting tracer and connections controlling the strength of the currents traversing the tracer lines as the transmitting tracer is moved over its writing surface, a receiving pen, pen-moving parts therefor including consequent pole magnets provided with movable coils connected with the tracer lines and with the receiving pen. 70
  4. In a telautographic system of the variable current-strength type, the combination with tracer lines connecting the transmitter and receiver, a current supplying circuit, a transmitting tracer and connections for shunting therefrom into the tracer lines currents varying in strength as the transmitting tracer is moved over its writing surface, a receiving pen, pen-moving parts therefor including consequent pole magnets provided with movable coils connected with the tracer lines and with the receiving pen, and a source of electric energy for stationary windings of said magnets. 80
  5. In a telautographic system of the variable current-strength type, the combination with tracer lines connecting the transmitter and receiver, a current supplying circuit, a transmitting tracer and connections for shunting therefrom into the tracer lines currents varying in strength as the transmitting tracer is moved over its writing surface, a receiving pen, pen-moving parts therefor including consequent pole magnets provided with movable coils connected with the tracer lines and with the receiving pen, and a source of electric energy for stationary windings of said magnets. 90
  6. In testimony whereof, I have hereunto set my hand in the presence of two subscribing witnesses.
